UNITED STATES PATENT OFFICE.

ROBERT H. RAMSEY, OF COBOURG, CANADA.

IMPROVEMENT IN CAR-TRUCK-SHIFTING APPARATUS.

Specification forming part of Letters Patent No. 178,079, dated May 30, 1876; application filed February 14, 1876.

To all whom it may concern:

Be it known that I, ROBERT HENRY RAMSEY, of Cobourg, in the county of Northumberland, in the Province of Ontario and Dominion of Canada, have invented a new and Improved Car-Truck-Shifting Apparatus, of which the following is a specification:

My invention consists of a couple of trucks on each side of the truck on which is the car whose trucks are to be shifted, carrying a beam extending across from one to the other under the car-body at each end, in combination with a depressed portion of the main truck, down which the trucks to be removed run, and detach from the car, which runs on the beam carried by the side trucks, which run at the same time on level tracks. The trucks to be connected are run up the grade, and thus brought into connection with the car.

Figure 1 is a longitudinal section of the depressed railway and beams, and side elevation of the trucks, showing my improved shifting contrivance, the section being taken on the line *x x* of Fig. 2; and Fig. 2 is a transverse section taken on the line *y y* of Fig. 1.

Similar letters of reference indicate corresponding parts.

A represents level outside tracks along the depressed main track *B*. *C* is the car-body from which the trucks *D* are to be taken. *E* are the trucks on the outside track, and *F* the beams for carrying the car-body on them. By

running trucks *D* into the depressed part *B* of the main track they descend so as to clear the king-bolt *G*, and thus disconnect from the car, and to connect other trucks they are moved up out of the depressed part along with the car *C*, so that the king-bolt will enter the hole for it in the bolster of the truck.

Tracks of different gages will be laid in the depressed way for changing the trucks for roads of different gages.

The main track may be level, and the side tracks *A* may be elevated and operate in the same manner; but I prefer the arrangement shown, because it is easier to move the car along the level road and the trucks up the inclines than to move the car over the elevations.

For shifting trucks of different gages the apparatus will be found very efficient and economical.

Having thus described my invention, I claim as new and desire to secure by Letters Patent—

The combination, with car, of a beam placed under each end thereof, and supported by trucks that roll on tracks outside of and on a higher plane than the main track, substantially as and for the purpose specified.

ROBERT HENRY RAMSEY.
